UNITED STATES PATENT OFFICE.

MAX GARBELL, OF CHICAGO, ILLINOIS, ASSIGNOR TO GARBELL TYPEWRITER CORPORATION, OF CHICAGO, ILLINOIS, A CORPORATION OF DELAWARE.

TYPEWRITING MACHINE.

Application filed February 24, 1920. Serial No. 360,598.

To all whom it may concern:

Be it known that I, MAX GARBELL, a citizen of the United States, residing at Chicago, in the county of Cook and State of Illinois, have invented certain new and useful Improvements in Typewriting Machines, of which the following is a specification.

The invention relates to a mechanical writing machine or typewriter and is particularly applicable, although not necessarily limited to use on typewriting machines of a character exemplifying compactness of mechanism and being hence readily portable, as shown for example in patent of the United States No. 1,305,893 granted to me on June 3, 1919, on a front strike or visible typewriter.

It is the primary object of the invention to provide improvements in the construction 20 of a writing machine of the described character whereby the support or carriage for the type platen and the various instrumentalities carried thereby including connections from the key board for actuating the escapement mechanism, may be quickly and conveniently released from their actuating devices on the machine or main frame for permitting the removal of the carriage either for the purpose of substituting a similarly 30 constructed carriage of different width, or for convenience in cleaning the machine or preparing it for transportation, and the like.

Other objects of the invention will be set forth in the following description of the 35 preferred embodiments thereof with reference to the accompanying drawings, the novel features being defined in the subjoined claims.

In the said drawings, Fig. 1 is a top plan 40 view of a writing machine embodying the invention, the key board and adjacent parts being broken away. Fig. 2 is a vertical section looking toward the platen carriage mechanism as indicated by the arrows on section line 2-2 of Fig. 1. Fig. 3 is a rear elevation of the platen carriage and adjacent mechanism with frame and other parts in section or omitted, while Fig. 4 is a similar view showing the platen carriage release 45 mechanism operated so as to permit the removal of the carriage from the main frame. Fig. 5 is a horizontal section through the lower part of the machine looking downwardly and Fig. 6 is a transverse vertical section parallel with the key bars, both

views showing details of the platen carriage supporting and releasing mechanism. Fig. 7 is an enlarged fragmentary view of a section on line 7-7 of Fig. 3 showing details of the carriage release actuating mechanism. 60 Fig. 8 is an enlarged fragmentary detail of the detachable connection for releasing the escapement from its actuating devices on the machine frame. Fig. 9 is a sectional view similar to Fig. 6 greatly enlarged to 65 illustrate details of the connections between the keyboard actuating devices and the detachable platen carriage and its supporting means, and Figs. 10, 11 and 12 are details in perspective of said connections. Fig. 13 70 is a view similar to Fig. 3 showing a modified construction of the platen carriage release mechanism and Fig. 14 is a view of the same mechanism as shown in Fig. 13, the same being shown operated to the releasing 75 position. Fig. 15 is a detail on section line 15-15 of Fig. 13. Figs. 16 and 17 are details in section on the carriage releasing and locking shift rod and Fig. 18 is a section through the same on line 18-18 of 80 Figure 13, while Figs. 19 to 21 inclusive are detail perspective views of parts of the same structure.

While in the drawings the invention is shown in its preferred form as applied to a 85 front strike or visible typewriter it may obviously be used with other types of writing machines.

The type bars 10 are mounted to reciprocate in a bridge or arch 11 of segmental 90 form following the construction of type bar action shown in my prior patent referred to, and carry types with printing faces 10a adapted to strike a common printing point on cylindrical platen 12 through a guide 13 95 carried by one or both of two inwardly projecting or overhanging plates 14, 15 formed integral with side bars 16, 17 of the main frame. The segment arch 11 is secured also to the plates 14, 15 by screws 16x and the usual printing ribbon spools 28, 29 are also conveniently carried by said plates so that the printing ribbon may be presented between the platen and the type at the printing point in the conventional manner. The 105 reciprocating type bar action, referred to, permits the platen carriage to be mounted unusually low on the main frame so that the side bars 16, 17 thereof are relatively narrow or low to clear the same, and these 110

side bars are preferably connected by an integral back member 18 and the usual front rail surrounding the keyboard not shown. The main frame may be provided with the 5 usual legs for supporting same on a surface, in the form of the short depending lugs near the four corners of the rectangular frame, the two at the rear side of the frame being shown and designated by the reference characters 19, 20. The cylindrical type platen 12 is rotatably mounted in a carriage for presenting different or successive lines of its printing surface to the type printing point, and to enable the platen to have the usual 10 longitudinal movement in relation to the printing point the platen carriage is mounted on a support which has a vertical movement so that when the type faces 10^a are elongated and carry a plurality of type 15 characters it is possible by the usual vertical shift of the platen to have any one of the three characters on each of the type faces presented to the printing point on the platen. The type characters are not shown 20 on the type 10^a since the same forms no part 25 of the present invention.

The mechanism for supporting and shifting the platen consists of a compound device comprising a vertically shiftable supporting frame provided with a track over 30 which the platen carriage is adapted to be moved in a longitudinal direction and from side to side of the frame in the conventional manner. This mechanism for supporting 35 the platen has movement in the vertical direction on a pair of parallel rails vertically arranged and secured to the back bar of the main frame 18 as indicated by the reference characters 30, 31, Figs. 2, 3 4, 5 and 6. 40 These vertical rails 30, 31 are flanged or widened as shown in the sectional view Fig. 5 at their forward extremities to afford retaining means for the anti-friction devices by which the sub-frame of the platen carriage has its vertical movement on these 45 rails 30, 31. The sub-frame of the platen carriage is preferably made up of two spaced triangular members 32, 33 each having two pairs of lateral projections and each 50 contiguous pair of projections being spaced apart the normal width of the body part of the vertical carriage rails 30, 31, and carrying pins supporting the anti-friction rollers 34, 35. The said spaced branches of 55 the frame supporting these anti-friction devices are shown only in Fig. 6 and 9 as indicated by reference characters 36, 37. In Fig. 5 only the lower pairs of spaced branches 37 are shown and in order to co-operate most 60 advantageously with the rails 30, 31 it will be seen that only one anti-friction roller 35 is provided at the front of each rail but that the parts 36, 37 are divided with one branch of each extending on opposite sides of the 65 rails and each branch provided with one of

the anti-friction rollers 34. This construction provides a supporting frame which may be easily shifted in vertical directions and sufficient rigidity may be given to such frame by reason of the fact that the top legs of 70 each of the triangular members 32, 33 are joined by a pair of carriage rails which may be formed of composite parts as indicated by reference characters 38, 39 having troughs or grooves opening upwardly as 75 shown most clearly in Figs. 6 and 9, such troughs or grooved portions of the rails of the carriage sub-frame being adapted to serve as ball races for the anti-friction ball bearings indicated by reference characters 80 40, 41. Co-operating with the anti-friction devices carried in these grooved rails 38, 39 are the similar inverted rails 42, 43, the latter being connected to the platen frame proper. The latter will be provided with 85 end members 44, 45 into which the trunnions at the extremities of the platen will be journaled so that the platen will have its customary rotations in its frame either by hand through the hand operating knobs 90 50, 51 or through the usual line space mechanism consisting of a suitably operating pawl indicated by reference character 52 co-operating with ratchet wheel 53 connected to rotate with the platen. The platen 95 120 may be provided with paper fingers or retaining devices of any desired construction such as indicated by reference characters 56, 57, Figs. 1, 2 and 6. The parts 100 or fingers 56 57 may be adjustably mounted on the connecting rod 60 extending between the end members 44, 45. At the lowest extremity of the sub-frame made up of the triangular members 32, 33 there are provided means as the pins 63 designed to be received in slots 64 formed in the outer ends of the platen shift levers 65. Obviously whenever the key bar lever 65 with the key 105 66 thereto attached is depressed the opposite extremity of the platen shift lever, which is pivoted on the shaft 67 fixed in the main frame 16, will tend to elevate the sub-frame made up of the connected triangular pieces 32, 33 and as this frame travels along the 110 vertical rails 30, 31 the platen frame and the platen and paper feed devices carried thereby will be vertically shifted.

On the platen frame illustrated 68 indicates a paper guide having a lower portion concentric with the cylindrical surface of the platen and being projected at the rear of the platen vertically and rearwardly to serve not only as a guide but as a paper table. It is preferred that the paper guide and table 68 be adjustably supported by the transverse member 69 pivotally mounted in the end members 44, 45 of the platen frame and controlled by the lever 70 extended toward the forward or front edge of the platen frame 115 to be of convenient access to the operator. 120 125 130

The paper table and guide 68 may also carry one or more supplementary guide rollers as indicated by reference character 71 (Fig. 6) and similar supplementary rollers as indicated by reference character 72 for co-operating with the platen on the upper and forward side thereof are rotatably supported by the paper fingers 56, 57. The shafts 60 and 69 are preferably so related that when 5 one of them is actuated, as through the hand lever 70, both will be synchronously rotated but in opposite directions to cause the paper table and guide 68 to be separated from the periphery of the platen on the lower side 10 while the paper fingers 56, 57 carrying the rollers 72 will also be caused to lift from the platen surface to permit the insertion of the sheet to be written upon by the machine. Such operation may be secured by the use 15 of a spring arm 73 (Fig. 6) secured to shaft 69 and bearing against the squared shaft 60 carrying the paper fingers 56, 57, as indicated at 74, Fig. 6. It will be noted that the spring arm 73 has a curved end at the point 20 of contact 74 which, when the shafts 60 and 69 are in normal position, engages above the center line of the shaft 60, thereby tending to hold the fingers 56—57 in proper position. When the shaft 69 is rotated clockwise, the 25 point of contact between the spring arm 73 and the shaft 60 drops down below the center line of the latter and acts to oscillate the shaft 60 in a counterclockwise direction. The end member 45 of the platen frame may 30 conveniently be provided with an inward extension as indicated by reference character 75, Figs. 1 and 2, to act as a finger rest or grip for the downward movement of the outer extremity of the hand lever 70 controlling the paper fingers and table of the 35 paper feed mechanism co-operating with the platen.

Since the details of construction of the platen and its supporting mechanism form 40 no important part of the present invention further details of construction of these parts are not described in detail except to call attention to the fact that the platen frame will in the usual manner be under the control 45 of a motor spring not shown, by which the platen frame may be moved longitudinally of its supporting frame on the anti-friction roller bearings 40, 41, such relative movement being under the control of the escapement mechanism. 76 is a toothed bar extending parallel of the platen and between the end members 44, 45 of the platen frame, the teeth thereon being constantly engaged by a toothed gear 77, the latter being actuated 50 by the motor spring. The action of the motor driven gear 77 meshing with the toothed bar 76 will be under the control of the usual escapement pinion rotatably connected with the escapement wheel 78, the latter being toothed and being adapted to have

one of the teeth thereon in constant engagement with the escapement mechanism consisting of the pivotally mounted yoke 79 carrying the fixed tooth 80 and having secured thereto a reciprocating member 81 carrying 50 a second pawl adapted also to engage one tooth at a time of the escapement pinion 78. The member 81 carrying the integral movable dog may be mounted to have the desired reciprocating movement on pin 84 on yoke 79 by being provided with a slot indicated at 82, Fig. 3, there being a spring 83 interposed between this member and the yoke 79. By reason of this construction the normal 55 tendency of the spring driven gear 77 will be to shift the platen frame in relation to its carriage and such shifting will obviously cause the rotation of the escapement toothed wheel 78, which latter will be controlled against permitting any movement whatever 60 of the platen frame except as such movement is permitted by reason of the rocking action of the escapement yoke 79, which will permit the rotation of the escapement gear 78 one tooth at a time in a well known manner. The escapement yoke is pivoted at 86, 87 to oscillate in a suitable depending yoke 88 carried by the platen carriage frame and removable with said platen carriage frame 65 when the latter is disconnected in the manner hereinafter described from the typewriter main frame. The oscillation of the escapement yoke or rocker 79 in order to produce the necessary feed of the escapement mechanism will be secured through the reciprocating link or bar 89, Figs. 2, 3, 4, 5 and 6, the oscillation of this link or bar 89 being the result of its connection with the universal bar 90, the latter being in the form 70 of a bail pivoted at its extremities to 105 shaft 67.

The rearwardly extending extremity of the link or bar 89 is especially constructed and controlled to permit of its detachment from the depending branch of the oscillating escapement yoke or rocker 79. This is desirable in connection with my invention where it is desired to remove not only the platen carriage and its support from the main frame of the machine at will, but also 110 to remove therewith the escapement mechanism carried in my preferred construction by the platen carriage support. To accomplish this result the downwardly extending branch 79 of the escapement yoke is provided with an angularly turned extremity which may be perforated as indicated at 79^a, Fig. 5, and adapted to receive a pin 89^a fixed to the rearward extremity of the link or bar 89. This will provide an operable connection between the operating link or bar 89 and the escapement yoke, the bar 89 being kept in engagement with the lower extremity of the yoke by reason of a fork or keeper 115 preferably consisting of a tubular portion 120

91 fixed to a shaft 92 supported at its extremities by or adjacent to the end members 16 and 17 of the main frame. The part 91 will preferably be provided with spaced upwardly extending branches 93, 94 adapted to receive the bar or link 89 therebetween and hold the same so that the pin 89^a therein will normally engage the corresponding hole or recess in the depending branch of the escapement yoke. At the same time the construction will provide for the disconnection of the escapement mechanism from its actuating bar 89 upon attempted release of the carriage and its support from the main frame, for the reason that the shaft 92 is preferably mounted to reciprocate and the sleeve 91 and the spaced branches 93, 94 comprising the keeper or yoke for the escapement operating link or bar 89 will be capable of longitudinal movement in relation to the ends 16, 17 of the main frame.

The shaft 92 will preferably have secured thereto the combined platen carriage locking devices and case shift stop members 95, 96, the latter having hub portions as indicated in Figs. 2, 3 and 4, and also carrying the fixed projections 97 and 98 adapted to engage fixed stops 99 secured to the spaced triangular frame members 33 of the platen carriage sub-frame or support. Each of the stop members 95, 96 being keyed to the shaft 92 and the latter being rotatable in the main frame it will be seen that the vertical height to which the platen carriage may be raised on the vertical rails 30, 31 will be determined by the position of the stop members 95, 96. In other words, each of the types, as already explained, will be provided in a well known manner with three spaced characters, the characters of one set being preferably the upper case letters, while a second position on each of the types will be given over to the lower case letters, while a third position throughout the series will be given to numerals and such characters as punctuation marks. The normal depressed position of the platen carriage and its support on the vertical rails 30, 31 will position the platen so that the types will print the lower case letters, while the upper case letters may be brought into the range of the printing point on the type platen when the carriage is raised until the fixed stops 99 are caused to engage the lower stop members 95—96. A further shifting of these members, by depressing the figure shift key 66^a, will bring the upper stops 97 thereon within the path of the vertically moving stops 99 and obviously carry the stops 98 out of the path of said fixed stops 99 since the stops 97 and 98 on each of these devices will be offset and the result will be that upon the proper positioning of these carriage stops or positioning devices 95, 96 will depend the degree of elevation to which the type platen and its

carriage and support may be elevated by means of the platen shift keys 66 and 66^a.

The bar or shaft 92 will preferably be journaled in the vertical rails 30, 31 and the carriage stop device 96 will be rigidly secured to the shaft, while the stop device or member 95 will be preferably secured to a sleeve 100 having an enlargement or flange 101, both said sleeve and said flange being squared or splined on shaft 92 and being slidable thereon under the control of a coil spring 102 interposed therebetween and the end frame member 16. A spring 103 will also be interposed between the platen carriage stop member 96 and the end member 17 of the main frame and there will be a sleeve 104 carrying a flanged member 105 similar to the flange 101 secured to the shaft 92 and spaced apart from said flange 101, both said flanges being preferably on opposite sides of the vertical rail member 31 and an actuating device or cam 106 is pivoted to the vertical rail 31, there being an arm on said cam member having attached thereto a link 107 slidable in an opening in the end frame 16 and carrying a button or hand actuating device 108 on its outer extremity so that when an operator pulls outwardly upon the hand device 108 the effect will be to separate the sleeves 100, 104 with the result that the shaft 92 will be shifted toward the right as indicated in Fig. 4, compressing the spring 103 and at the same time the camming action of the part 106 will cause the platen carriage stop 95 to be shifted outwardly compressing the spring 102. This movement will carry the platen support limiting stops out of the path of movement of the projections 99 on the platen carriage sub-frame, thereby allowing the release or removal of the platen carriage and its support from the main frame, while the same movement of the shaft 92 will disconnect the end of the escapement actuating link, or bar 89 carrying its pin 89^a from the escapement yoke.

The above description will be sufficient to indicate the manner in which the platen carriage and its support may be disconnected and removed entirely from the machine main frame, for it will be seen that all it will be necessary for the operator to do to accomplish this result will be the actuation of the mechanism controlled by the hand operated key 108 and the simple withdrawal of that key through the actuation of the cam 106 will put the connections between the key board and the escapement rocker as well as the ordinary carriage stop devices in such position that the operator will be free to lift the platen carriage with its supporting mechanism together with the escapement rocker and related mechanism entirely free of the machine. This result is attained in connection with another important fea-

ture of the invention which has to do with the special construction of the back spacer provided by me.

This back spacer mechanism requires no disconnecting means but is at all times in such position and condition that it permits the withdrawal or removal from the machine frame of the platen carriage and its supporting device from the machine main frame and the vertical rails 30, 31 without disturbing the position of any of the parts and leaving and retaining the connections both on the machine main frame and on the platen carriage support in such position that the platen carriage and its support may be replaced without the likelihood or possibility of the parts becoming out of alinement or adjustment. This special construction may be seen from the disclosure in Figs. 3 to 6 inclusive and from which it will be seen that the usual back spacer lever key 110 is provided, the same being pivoted on the shaft 67 and having an operative connection by means of a slot therein indicated by reference character 111 with pin 112 on the back spacer lever 113 pivoted at 114 to the side frame of the machine. This lever 113 extends to a point adjacent the back member 18 of the main frame where it is pivotally connected with a vertical link 115 connected by pivot with the apex of a right angular lever 117, the extremity of one leg of which is pivoted at 116 to the vertical carriage rail 31. The other leg of this member 115 extends vertically and is elongated in order to present a considerable portion of length to be engaged by a roller or other anti-friction device as indicated at 118 on the extremity of the back spacer pawl link 119, the latter extending to a position immediately in front of the motor spring gear 77 where it is pivotally connected at 120 with the back spacer dog 121, the latter being provided with an integral pawl as indicated at 122 adapted to engage the teeth on the rack 76 which normally engages the motor gear 77 for driving the platen frame. The dog 121 is slotted and is supported by a pin 123 which is fixed to the rocker support or bracket 88. It will be seen that upon the depression of the back spacer key 110 the pivoted angular member 117 will be oscillated on its pivot reciprocating the back spacer pawl link 119 and this will overcome the normal tension of the spring 124 which is designed to be relatively stronger than the spring 125 shown in dotted lines in Fig. 3, as being of the compression type and interposed between the back spacer pawl link 119 and the dog 121. The effect of the overcoming of the tension of spring 124 will result in the compression spring 125 elevating the dog 121 until the fixed pawl 122 thereon engages the teeth of rack bar 76 whereupon further movement of the back spacer pawl

link under the control of the operator's key will result in shifting the platen carriage a predetermined distance, which is preferred to be one letter space of the carriage. Obviously, the carriage may be moved by the back spacer in retrograde direction as many spaces as the back spacer key is consecutively worked. The fact that the angular pivoted member 117 with its vertical extending branch is pivoted to the fixed vertical carriage rail will enable the platen carriage to be moved vertically independent thereof and since the escapement rocker and its supporting means is carried by the platen carriage support as well as the back spacer pawl link 119, it will be apparent that the construction admirably lends itself to the ready detachment of the platen carriage and the back spacer pawl link from its actuating device consisting of the vertical leg of the angular member 117. The latter will obviously be positioned whenever the back spacer key is released so that the free leg or branch thereof will normally stand in approximately a vertical position and in order to insure that the free end of the back spacer pawl link including the anti-friction roller 118 thereon will be held in proper operative position at all times whether the platen carriage and its support is attached or detached, with respect to the main frame, I prefer to provide a sliding support as indicated at 126, the latter being supported by one of the lower carriage rails.

Reference has been made to the reciprocating escapement link 89 actuated from the universal bar 90. The latter it will be seen by reference to Figs. 5 and 6 is pivotally connected at its extremities to the shaft 67 and underlies each and every one of the type key levers on the machine key board. It does not underlie the key levers 65 or 66^a nor the back spacer key lever 110. The connection between the escapement operating link 89 and the universal bar is provided through a bell crank lever 130 pivoted at 131 to the underside of one of the top supporting members 14 or 15 adjacent the key board on the main frame. At its free end it is connected by link 132 which is in turn pivotally attached to the universal bar 90.

The manner in which the proper shift of the platen carriage and its support is procured for varying the printing point in order to accomodate the platen to the three printing positions of printing characters on the types through the use of the shift key levers 65 and 66^a has been referred to, but the special construction of the connections between the rear ends of these levers and the lower extremities of the platen carriage support will be further described particularly in connection with the disclosure as contained in the detail views Figs. 9 to 12 130

inclusive. In Fig. 10 is shown the detail of the rocking carriage stop devices 95, 96 that are adapted to rock synchronously with the shaft 92. These devices carrying the stops 5 or lugs, 97, 98 are actuated by links 140, 141 adapted to be reciprocated by connection with the shift key levers 66^a, the effect of which is to position the stop devices 95, 96 in either of two positions as shown by the 10 full and dotted lines in Fig. 9. The lower extremities of the rocking devices 95, 96 are given a special formation as shown in Fig. 10, there being a tongue 95^a formed at the bottom with an adjacent slot adapted to 15 receive the headed pin 143 on the link 141, the latter having a tongue 142 preferably formed integrally therewith and opposing a similarly formed tongue 95^b formed as an extension as shown in Fig. 10 at the bottom 20 of the oscillating locking device 95. When the pin 143 is inserted in the slot at the bottom of the part 95 the parts may be retained in normal operative position by placing a coil compression spring with the extremities 25 of the same on each of the parts 142 and 95^b, such a spring being designated by reference character 144 in Figs. 5 and 9. In Fig. 9 two positions of the platen carriage are illustrated, one being in full lines and the other in dotted lines. In the lowermost position the platen carriage and its support will occupy relatively the position the parts assume in Fig. 3. When it is desired to 30 shift the platen carriage to print in the intermediate position the movement of the shift key lever 66 will elevate the platen subcarriage and the members 95, 96 are normally positioned so that the lugs 98 thereon will engage the projections 99 on the platen 35 subframe positioning the carriage for lying in the intermediate position and utilizing the intermediate characters on the type faces. When it is desired to print with the platen carriage and its frame at the upward limit 40 of its movement the devices 95, 96 will be oscillated by means of the shift keys 66^a until the uppermost lugs or projections 97 will engage the projections 99 on the carriage frame thus positioning the platen carriage in its uppermost position and enabling 45 the type characters at the opposite extremity, usually the upper case letters, to meet the printing point on the platen.

The platen shift levers 65 are obviously 50 constructed in duplicate, there being one located at each side of the main frame adjacent the the side members 16, 17 thereof and it is only necessary for the operator to 55 actuate one of these levers in order to control the position of the platen carriage and its supporting device, both key levers 65 and the key 66 attached thereto obviously working in unison. The platen shift lever 65 is mounted to have movement independently of 60 the supplementary platen shift lever 66^a but

is so constructed as to be capable of shifting the platen carriage and subcarriage on its rails only about half the normal possible length of its shift. In other words, the function of the levers 65 will be when not operated to permit the carriage to position the platen in its lowest writing position, while the actuation of the lever 65 by means of the key 66 thereon will have the effect of elevating the platen carriage and its subframe including the platen thereon to the intermediate writing position only since at all times when the lever 65 only is actuated the stop devices 95, 96 will be positioned so that stops 98 will be interposed in the path 70 of the fixed stops 99 on the carriage subframe thus blocking further upward movement of the platen carriage and its supporting means. The supplementary platen shift levers 66^a are likewise pivoted to shaft 67 along side the levers 65 but they do not extend to the rear of the machine beyond such pivotal connection with the shaft 67. In order to make them effective however, they are normally held in elevated position by spring means, not shown, in a manner similar to the elastic means controlling the ordinary key levers and these levers 66^a are in addition each provided with overhanging lugs 66^b which overlie the tops of 75 the levers 65. From this construction it follows that the depression of either of the key levers 66^a at either side of the key board will have the effect of starting the depression of the lever 65 or, if said lever has been already depressed to the intermediate position so that the platen carriage and subframe are partially elevated, the depression of the key levers 66^a will not be effective to 80 shift the levers 65 and the platen until such time as the overhanging lugs or projections 66^b on the levers come in contact with levers 65. An important feature of this construction which makes it possible for the depression of levers 66^a to shift the platen carriage 85 and its subframe through the activation of the shift levers 65 resides in the provision of links 140, 141 which are pivoted to a part of the lever 66^a eccentric to their pivotal connection with the shaft 67 from which it results that a depressing movement of the levers 66^a will reciprocate the links 140, 141 toward the rear of the frame of the machine 90 and these links, being pivotally connected with the lower extremities of the pivotally mounted stop devices 95, 96 on shaft 92, will actuate the intermediate stops 98 out of the path of the fixed stops on the platen subframe and enable the platen with its carriage and subframe to be elevated to the full 95 normal height or one step above the intermediate printing position.

Reference has been made to the detail construction of the connection between links 140, 141 and the lower ends of the locking 100

- devices 95, 96. It will be apparent that the elastic or resilient connection is very desirable since otherwise the first part of the downward movement of the key lever 66^a effect the positioning of the locking devices 95, 96 and it will be apparent that without the elastic connection including the springs 144 further downward movement of the key lever 66^a would be impossible and there would consequently be a binding of parts and inability on the part of the operator to operate the platen carriage and subframe to the highest lift or position of which it is desirable and capable of being moved.
- 15 When it is desired to remove the carriage from the main frame and associated mechanism of the machine, it will be apparent that the actuation of the button or hand device 108 causes separation of the flanged collars 100 and 104, thus separating the stop members 95, 96 in the manner indicated in Fig. 4 until the co-operating stops thereon and on the carriage will be out of the path of each other. Obviously, the same longitudinal movement imparted to the shaft 92 will disengage the link 89 and the pin 89^a therein from the escapement rocker device, whereupon the carriage with its subframe may be moved along the vertical rails and entirely disconnected from the machine frame, the back space mechanism including the link 119 and the roller 118 thereon disengaging by reason of the sliding of the roller 118 along and off the end of the vertical leg of the back space actuating arm 117 which will remain attached to the vertical rail 31. This is an important feature in the construction of a machine of this character since it enables the carriage including the subframe together with the escapement mechanism and back spacing mechanism to be removed and separately packed from the main frame and key board mechanism in shipping often saving injury to the parts due to rough handling. Perhaps the most important feature of this construction and the invention contained therein resides in the fact that such construction enables the owner or operator of such machine to quickly detach the platen carriage and its support from the main frame and key board mechanism and to substitute therefor a platen carriage and subframe of a different width. This construction, for example, enables the owner of the machine to buy same equipped with a platen and carriage of standard letter sheet width and afterwards adapt the machine by the purchase of only an additional platen and carriage to the writing of pages of any unusual width.
- In Fig. 12 is shown the special construction of the rearward extremity of the key levers 65 which actuate and support the platen carriage subframe. It will be seen that the extremities of these levers 65 are slotted and the branches 65^a are offset out of the plane of the body portion of the lever 65 a less distance than the length of the pin 63 which serves as a connection with the platen subframe. There is also an offset in the branch 65^b a greater distance than the length of the pin 63 and the extremity of this branch is then extended a short distance parallel with the body part of the lever. This special formation in the extremities of the levers 65 enables them to be disconnected from the pin 63 at the lower extremities of the platen carriage subframe upon the shifting of the release shaft 92, which is accomplished for the reason that the extremities 65^b extend to a position where they contact with the body part of the members 95, 96 and lie adjacent the outer edges of these respective members so that as they are operated and consequently separated against the springing action of those portions of levers 65 to the rear of pivot 67 by shifting of the device to the unlocking position, the effect will be to disconnect the members comprising the carriage subframe from the actuating levers 65 and to disconnect escapement actuating link 89 whereupon the carriage and its subframe will then be free to move upwardly and off from the main frame of the machine. This offsetting of the parts 65^a of levers 65 is important in insuring that the pins 63 of the carriage subframe will, upon insertion, always rest flush upon the upper sides of the lower branches of lever 65 which branches terminate in the offset portion 65^b and also so that upon restoration of shafts 92 or 150 to normal positions shown in Figs. 2, 3, 9 and 13, proper alignment of slots 64 with pins 63 is insured.
- In Figs. 13 and 14 together with the fragmentary detail views 15 to 21 inclusive is illustrated the construction of a carriage release mechanism similar in principle to the form heretofore described and shown particularly in Figs. 3 to 5 inclusive. I prefer in some respects for practical manufacture and simplicity and directness in operation the modified form in which I employ the same shifter fork hub 91 with branches 93 and 94 thereon as already shown and described. I vary the construction of the shaft, which is indicated in Figs. 13 and 14 by reference character 150. This shaft is mounted to reciprocate longitudinally of the main frame in the same position as the shaft 92, heretofore described and it has rigidly secured thereto the carriage shift stop member 96 having the shift stops 97-98 thereon. An operating member having one end knurled as indicated at 151 is journaled to slide longitudinally in a thickened or hub portion 17^a at one side of the machine frame, there being a cylindrical reduced portion 151^a cooperating with the hub portion 17^a, the reduced portion of the hand piece being bored

to take the end of the shaft 150 which is secured therein by pin 152. In order to position the shaft 150 in relation to the main frame the hub part 17^a will be provided with a slot 17^b in which will be an elastic locking member in the form of a wire as indicated at 153 suitably secured to the frame and adapted to co-operate with one or the other of two peripheral slots 151^b and 151^c in the 10 adjusting member 151. In this way the shaft 150 will be firmly held in either of its adjusted positions indicated by the positions of the parts in Figs. 13 and 14 respectively. The longitudinal shifting of shaft 150 will 15 obviously carry the carriage shift stop member 96 and the stops thereon and in order to shift the member 95, the latter is mounted on a hub portion 155 which is perforated to reciprocate freely on the squared end of the 20 shaft 150. This may be accomplished by providing a grooved ring or keeper 156 which may be secured on the extended hub portion of the part 155 by riveting or welding the outer end thereof as indicated in Fig. 16. In the groove or keeper 156 the forked end of lever 157 engages, and the latter is pivotally connected at 158 with the lever 159 fulcrumed at 160 to the vertical carriage rail 31. At its other extremity at 25 161, the lever 159 is pivoted to an arm of the shifter fork 162, the latter engaging a groove in the collar 163, which is pinned or otherwise secured at 164 to shaft 150. By this construction it will be seen that when 30 over the operator by pulling upon the knob or hand device 151 shifts the shaft 150 so that the elastic locking wire or pawl 153 is caused to engage with the groove 151^c as illustrated by the position of the parts in Fig. 14, the effect will be to carry the shift 35 stops 97, 98 out of the path of stop members 99 on the platen carriage subframe thus releasing the platen and its subcarriage and enabling its detachment from the machine 40 frame in substantially the manner hereinbefore described, since it will be seen that the same shift of the shaft 150 will disconnect the escapement feed actuating devices from their connections with the universal bar or 45 key board.

In order to limit the downward movement of the carriage in its lowermost position and to provide a certain amount of adjustment of same in relation to the main frame the 50 end members 16, 17 of the frame are provided with lateral projections 170, 171 (Figs. 2, 3 and 4) and these are perforated, threaded and provided with threaded stop devices 172 which are held in their adjusted 55 positions by lock nuts 173. Although it forms no part of the present invention claimed I show in Figs. 2 and 3 the usual alarm bell 180 for indicating movement of the carriage approaching the end of a line 60 and the alarm is given by means of the 65 sounding device or hammer 181 carried on the end of the irregular lever 182 pivoted at 183 to the bracket supporting the escapement mechanism on the carriage subframe. The vertically projecting branch 182^a of 70 the bell signal lever will be engaged when the platen is near the end of its run by a pawl 190 pivoted at 191 to an adjustable member 192 mounted upon one of the carriage frame members at the rear, as indicated by reference character 200. The bar 200 of the carriage frame also carries an adjustable member 201 having a margin stop in the form of a pawl 202 pivoted thereto. 75

In typewriting machines of the described character it is desirable to vary the line spacing for narrow, medium and wide spaces between the respective lines usually referred to as single, double and triple 80 spacing, and although same forms no part of the present invention claimed I show in connection with the carriage and platen of the machine an adjustment for the line space mechanism consisting of lever 210 having a 85 locking detent 211 thereon adapted to engage with openings or notches in segment 212. 90

The reference character 240 (Figs. 1 and 2) indicates a platen scale adjacent the printing point the same being attached to one of the rails or frame members of the subframe carriage. 95

Although same forms no part of the present invention claimed, there is also shown in Fig. 2 a ribbon supporting or shifting device adapted for a multi-colored ribbon, the same comprising the rotatable rod or shaft 250 having the hand adjusting member 251 at the left front side of the carriage, the 100 rod 250 being journaled to rotate in suitable supporting means carried by the subframe of the carriage, there being an offset portion 252 carried by the said rod or shaft in the nature of a crank to which is 105 pivotally connected a pair of ribbon supporting members 253, 254. The upper extremities of the ribbon supporting and guiding members 253, 254 are provided with 110 elongated slots as indicated at 255, 256 thus 115 adapting the multi-colored flat ribbon to be passed longitudinally through said slotted portions and insuring that the ribbon will be held or guided on each side of the printing point, its vertical adjustment with respect to the printing point on the platen being under the control of the adjusting lever 251. Since it is common to provide these ribbons in two colors, obviously, only 120 two adjustments of the lever 251 will be required, and the guides 255, 256 will be operative in one extremity for one color and in the opposite extremity of their movement for the other color. Reference character 260, Figs. 1 and 3 indicates a carriage 125 130

release operating lever which is rigidly attached to one end of carriage release bar 261. Release bar 261 is provided with a plurality of angular slots 262 and it is adjustably held in relation to the platen carriage frame by screws 263 passed through said slots. The result of this construction as shown most clearly in Fig. 3 is to cause the bar 261 when moved in one direction to be depressed and to be elevated when released. The lower edge of the bar 261 presents a longitudinal surface approximately parallel with the axis of the platen contiguous to the upper extremity of a T-shaped arm 265, which is pivoted preferably on the axis of the bell hammer lever 183. The free leg of the lever which is below and opposite the leg which engages the bar 261 is carried to a point adjacent the upper edge 20 of the escapement dog 81 which carries the fixed pawl 80 engaging the escapement ratchet 78. It will be seen that the depression of the bar 61 will be effective to disengage the escapement pawl 80 from ratchet 78 leaving the carriage free to be moved in either direction, that is, under the action of the propelling spring or in the opposite direction when the tension of the spring is overcome. The escapement ratchet 78 may conveniently be held in position on a journal pin or screw the head of which is indicated by the reference character 270 (Fig. 3), the body of the screw being threaded into a projection on the escapement supporting bracket 88 carried by the platen subframe. I prefer to utilize the screw or stud 270 as a stop for engagement by the marginal stops or devices of the carriage since the same is located conveniently midway between the lateral sides of the main frame, and in order to accommodate the screw 270 to this additional function the head portion thereof is somewhat elongated in practice being upwards of one eighth of an inch in length, and in order to enable the same to more securely hold the escapement ratchet 78 in position, I prefer to provide an enlargement or flange 271 at the base of the head portion 270, the same engaging and retaining the escapement ratchet 78 in its position on the stud and bracket. By this construction whenever the carriage reaches the limits of its movement toward the right as one faces the rear of the machine as the parts are shown in Fig. 3 the carriage will come to a stop when the marginal space lug 190 engages the head of screw 270, and likewise when the carriage is moved a corresponding distance in the opposite direction, the marginal stop 202 will engage the same part.

Although the structure of the type bar action employed in this construction is that shown in my patent referred to, it is not shown in detail nor referred to herein except to show the relative location of these parts. The support for the elastic means for normally elevating the key levers is shown in Figs. 3 and 5 being indicated by reference character 280. This part 280 is 70 constructed in approximately the form of a semi-circle and is supported by the rear of the main frame. The same is true of the curved member 281 to which the key levers are pivoted at their rearward extremities. 75

I claim:

1. In a typewriting machine, the combination with a main frame; of a platen; a platen carriage comprising a platen frame on which the platen is rotatably supported and a sub-frame upon which the platen frame is mounted to reciprocate lengthwise of the platen; means providing a slidable support for the platen carriage on the main frame to adapt the carriage for case shift movements; means for imparting case shifting movements to said carriage; means normally operative to connect said carriage and case-shift-movement-imparting-means; and means for rendering said connecting means 90 inoperative, whereby said case-shift-movement-imparting-means is completely disengaged from the platen carriage to permit removal of the latter. 95
2. In a typewriting machine, the combination with a main frame; of a platen; a platen carriage comprising a platen frame on which the platen is rotatably supported and a sub-frame upon which the platen frame is mounted to reciprocate lengthwise of the platen; means providing a slidable support for the platen carriage on the main frame to adapt the carriage for case shift movements; means, normally operatively connected with said carriage, for imparting case shift movements thereto; and means for disengaging said case-shift-movement-imparting means and the platen carriage, including a shaft slidably mounted in the main frame. 100
3. In a typewriting machine, the combination with a main frame; of a platen; a platen carriage comprising a platen frame on which the platen is rotatably supported and a sub-frame upon which the platen frame is adapted to reciprocate; escapement mechanism mounted on said platen carriage; means providing a slidable support for the platen carriage on the main frame to adapt the carriage for case shift movements; key-operated means carried by the main frame and normally operatively associated with the escapement mechanism for actuating the latter; key-operated case shift means mounted on the main frame and normally operatively 115 associated with said carriage to impart case shift movements thereto; and means for rendering both said case shift and escapement operating means, inoperative with relation to the platen carriage. 120

4. In a typewriting machine, the combination with a main frame; of a platen; a platen carriage including a platen frame on which the platen is rotatably supported and a sub-frame; means providing a vertically sliding support for the platen carriage on the main frame to adapt the carriage for case shift movements; an adjustable case shift stop device for normally retaining the platen carriage on the main frame and adapted also to determine the case shift position of the platen carriage; means, normally operatively associated with said carriage and with said device, for imparting case shift movements to the carriage; and means for rendering said last named means inoperative with relation to the platen carriage and said device.
5. In a typewriting machine, the combination with a main frame; of a platen; a platen carriage including a platen frame on which the platen is rotatably supported and a sub-frame; means providing a vertically sliding support for the platen carriage on the main frame to adapt the carriage for case shift movements; an adjustable case shift stop device for normally retaining the platen carriage on the main frame and adapted also to determine the case shift position of the platen carriage; means, normally operatively associated with said carriage and with said device, for imparting case shift movements to the carriage; escapement mechanism mounted on said platen carriage; key-operated means normally operatively associated with said escapement mechanism to actuate the latter; and means for rendering said case shift means inoperative with relation to the platen carriage and said device and said key-operated means inoperative with relation to the escapement mechanism.
6. In a typewriting machine, the combination with a main frame; of a platen; a platen carriage comprising a platen frame on which the platen is rotatably supported and a sub-frame upon which the platen frame is adapted to reciprocate; back-spacing mechanism mounted on said platen carriage and including a reciprocating bar; means for actuating said bar including a member mounted on the main frame of the machine, said member and bar being readily disconnectible upon removal of the platen carriage from the frame; means providing a vertical sliding support for the platen carriage on the main frame; adjustable means normally limiting the upward vertical movement of the platen carriage with respect to the main frame; and manually operable means for rendering said last named means ineffective to thereby permit removal of the carriage from the main frame.
7. In a typewriting machine, the combination with a main frame having vertically extending platen guiding means thereon; of a platen carriage vertically slidably mounted on said guiding means and removable therefrom; means for controlling the vertical position of said carriage with respect to the main frame, said means including a rock shaft, a member having stop lugs thereon rigid with said rock shaft; a cooperating stop lug on the carriage; and means for shifting said shaft with the member thereon to a position where the lugs of said member are out of the path of movement of the lug on the carriage to thereby permit the latter to be removed from the main frame.
8. In a typewriting machine, the combination with a main frame; of a platen carriage comprising a sub-frame vertically movably mounted on the main frame and a platen frame horizontally movable on the sub-frame, said carriage being vertically adjustable to different case positions; a key lever pivotally mounted on the main frame for imparting case shift movements to said carriage, one end of said lever having a detachable pivotal connection with said sub-frame; and means for temporarily disconnecting said lever from said sub-frame.
9. In a typewriting machine, the combination with a main frame having vertically extending guiding means for a platen carriage; of a platen carriage vertically slidable on said means and removable therefrom, said carriage including a sub-frame and a platen frame horizontally movable on the sub-frame; a case shift stop carried by said sub-frame; key-operated means for imparting case shift movement to said carriage; a shaft mounted in said main frame; a case shift stop member rigid with said shaft and having a plurality of differently located case shift stops thereon adapted to be positioned in operative relation with said case shift stop on the sub-frame, the stops on said members normally limiting the upward vertical movement of the carriage with respect to the main frame; and means for shifting said shaft axially to displace the stops on said member out of the path of the stop on the sub-frame.
10. In a typewriting machine, the combination with a main frame; of a platen carriage shiftable between three case positions on the main frame, said carriage having a case shift stop shoulder thereon; a case shift stop member at one side of said main frame having intermediate and upper case shift stop shoulders thereon cooperable with said stop shoulder on the carriage, the intermediate case shift stop shoulder on said member being normally positioned in the path of the stop shoulder on the carriage; and means for shifting said member to simultaneously move said intermediate case shift stop

shoulder to ineffective position and the upper case shift stop shoulder to effective position.

11. In a typewriting machine, the combination with a main frame; of a platen carriage vertically slidably mounted on the main frame and shiftable thereon between three case positions and also removable from the main frame, said carriage being provided with a case shift stop shoulder at one end; a case shift stop member mounted on the main frame and having a plurality of differently located case shift stop shoulders thereon adapted to cooperate with said stop shoulder on the carriage, one of said stop shoulders on said member being normally in the path of movement of the stop on the carriage; means for reversing the positions of said stop shoulders on said member with respect to the stop shoulder on the carriage; and means for displacing the stop shoulders on said member entirely out of the path of the stop shoulder on the carriage to thereby permit the carriage being removed from the main frame.

12. In a typewriting machine, the combination with a main frame provided with vertically extending platen carriage guiding means; of a platen carriage including a sub-frame vertically movable on said means, and a platen frame horizontally adjustable on the sub-frame, said sub-frame being provided with a case shift stop shoulder, said carriage being shiftable between three case positions on the main frame; a case shift stop member mounted on the main frame and having intermediate and upper case shift stop shoulders, the intermediate stop shoulder lying normally in the path of the stop shoulder on the sub-frame; key-operated means on the main frame normally operatively connected with the sub-frame to elevate the latter to intermediate case position; and key-operated means for simultaneously elevating the carriage to upper case position and adjusting said member to remove the intermediate stop shoulder thereon out of the path of the stop shoulder on the carriage and to bring the upper stop shoulder of the member in the path of the stop shoulder on the carriage.

13. In a typewriting machine, the combination with a main frame provided with vertically extending platen carriage guiding means; of a platen carriage including a sub-frame vertically movable on said means, and a platen frame horizontally adjustable on the sub-frame; said sub-frame being provided with a case shift stop shoulder, said carriage being shiftable between three case positions on the main frame; a case shift stop member mounted on the main frame

and having intermediate and upper case shift stop shoulders, the intermediate stop shoulder lying normally in the path of the stop shoulder on the sub-frame; key-operated means on the main frame normally operatively connected with the sub-frame to elevate the latter to intermediate case position; key-operated means for simultaneously elevating the carriage to upper case position and for adjusting said member to remove the intermediate stop shoulder thereon out of the path of the stop shoulder on the carriage and to bring the upper stop shoulder on the member in the path of the stop shoulder on the carriage; and manually operable means for simultaneously moving said stop member entirely out of the path of the stop shoulder on the carriage and disconnecting the operative relation between said key-actuated means and the carriage.

14. In a typewriting machine, the combination with a main frame provided with vertically extending platen carriage guiding means; of a platen carriage including a sub-frame vertically movable on said means, and a platen frame horizontally adjustable on the sub-frame, said sub-frame being provided with a case shift stop shoulder, said carriage being shiftable between three case positions on the main frame; a case shift stop member mounted on the main frame and having intermediate and upper case shift stop shoulders, the intermediate stop shoulder lying normally in the path of the stop shoulder on the sub-frame; key-operated means on the main frame normally operatively connected with the sub-frame to elevate the latter to intermediate case position; key-operated means for simultaneously elevating the carriage to upper case position and adjusting said member to remove the intermediate stop shoulder thereon out of the path of the stop shoulder on the carriage and to bring the upper stop shoulder on the member in the path of the stop shoulder of the carriage; escapement mechanism mounted on said carriage; key-operated means normally operatively associated with said escapement mechanism to actuate the latter, said key-operated means being disconnectable from the escapement mechanism upon the removal of the carriage from the frame; and means for simultaneously positioning said stop member in an inoperative position with respect to the stop shoulder on the carriage and for disconnecting the key-operated case shift means and the sub-frame.

In testimony whereof I have signed my name to this specification this 20th day of February A. D. 1920.

MAX GARBELL.
